UNITED STATES PATENT OFFICE.

CHARLES R. FARGO AND PAUL O. UNGER, OF KANSAS CITY, MISSOURI, ASSIGNORS TO IRVING-PITT MANUFACTURING COMPANY, OF KANSAS CITY, MISSOURI, A CORPORATION OF MISSOURI.

POSTING MECHANISM.

Application filed February 21, 1920. Serial No. 360,503.

To all whom it may concern:

Be it known that we, CHARLES R. FARGO and PAUL O. UNGER, citizens of the United States, residing at Kansas City, in the county of Jackson and State of Missouri, have invented a certain new and useful Improvement in Posting Mechanisms, of which the following is a specification.

Our invention relates to improvements in posting mechanisms.

The object of our invention is to provide a novel posting mechanism adapted for machine posting with which loose leaves may be easily and quickly manipulated and registered during the posting operation and reliably held in the registered position until they are clamped between the two binder members of an ordinary two post binder.

A further object of our invention is the provision of a posting mechanism, which is simple in construction, cheap to manufacture, durable, not liable to get out of order, and which is adapted for the registration of loose leaves which have lines of printed matter at right angles to the binder members and which in use in the binder are turned to the right or left after the manner of turning leaves of a book.

The novel features of our invention are hereinafter fully described and claimed.

In the accompanying drawings, which illustrate the preferred embodiment of our invention,

Fig. 1 is a perspective view of our improved posting mechanism, showing the arrangement of the leaves and of the binder members during a posting operation.

Fig. 2 is a perspective view of the posting mechanism, showing the posts partly inserted through the registered leaves.

Fig. 3 is a vertical sectional view with the binder removed.

Fig. 4 is a side elevation, reduced, of the mechanism, showing the clamping member provided with the posts resting on the movable leaf support.

Fig. 5 is a side elevation, partly broken away, showing the leaf support moved from the registering position and the leaves held clamped between the clamping members of the binder.

Fig. 6 is an enlarged vertical sectional view on the line 6—6 of Fig. 5.

Fig. 7 is an enlarged vertical sectional view on the line 7—7 of Fig. 5.

Similar reference characters designate similar parts in the different views.

1 designates one clamping member of an ordinary temporary binder having the usual two extension posts 2, adapted to slidably and lockingly engage the other clamping member 3 of the binder.

4 designates loose leaves adapted to be clamped between the members 1 and 3, each leaf having adjacent to at least one end edge two holes 5. As shown in the drawings, the opposite end edge may have adjacent to it two holes 6 which permit the sheet to be reversed, if desired, in the binder, the holes 6 being spaced apart the same distance as the holes 5. As shown in Figs. 1 and 2, the lines of printed matter 6' are at right angles to the binder members 1 and 3.

Respectively hinged to the members 1 and 3, are covers 7 and 8.

For properly positioning the clamping member 3 and its cover 8, so that leaves may be properly registered thereon in a posting operation with the lines of printed matter 6' running from left to right at right angles to the binder member 3, there is provided a support comprising a frame having two longitudinal side members 9 connected together by bolts 10 and a transverse positioning bar 11, against which is adapted to rest one end of the clamping member 3 and one edge of the cover 8 when the clamping member 3 is disposed longitudinally with respect to the members 9, as shown in Figs. 1 and 2.

For engaging the outer longitudinal edge of the member 3, to co-operate with the transverse bar 11 to properly position the member 3 longitudinally on the supporting frame and at right angles to the registering portion 17, one of the side members 9 has attached to it adjacent to the bar 11 an angular gage plate 12.

For supporting the loose leaves 4 during the posting operation and prior to registering them upon the clamping member 3 and cover 8, there is provided a leaf support, preferably longitudinally movable, and which may comprise two side members 13, which are connected by transverse bars 14, and each of which is provided in its up-

per edge with a V-shaped notch 15, in which is located one transverse portion 16, of an inverted V-shaped plate, the other transverse portion 17 being forwardly and downwardly inclined and adapted to engage and register one set of side edges of loose leaves 4, which rest on the clamping member 3 and the cover 8. The other portion 16 inclines downwardly and rearwardly and 10 serves to support the lower side edges of loose leaves 4, placed on the cover 7, when the latter is mounted in a forwardly and downwardly inclined position in the notches 15, as shown in Fig. 1. The transverse portion 15 which registers the side edges of the leaves, is disposed parallel with the transverse bar 11, which positions endwise the binder member 3.

The left end of the portion 17 of the registering plate, looking rearwardly, is provided with a right-angled forwardly extending flange 18 adapted to engage the edges of the leaves 4, which are adjacent to the holes 5, as shown in Fig. 1.

25 In order that the registering portion 17 and its flange 18 may be moved longitudinally rearwardly from the registering position shown in Figs. 1, 2, 3 and 4, to enable the clamping member 1 to be forced to the clamping position, shown in Fig. 5, the members 13 are longitudinally movably mounted on the side members 9 in any desired manner. In the structure illustrated, each side member 9 has attached to its upper edge, at the rear of the bar 11 a horizontal flat plate 19, Figs. 6 and 7 on which are mounted balls 20, which run in and support a longitudinal inverted V-shaped plate 21 which is secured to the lower edge 30 of the adjacent side member 13. One flange of the plate 21 has an outwardly extending extension 22, which is adapted to engage the lower side of the adjacent plate 19 to retain the side members 13 in their operative positions.

To retain the balls 20 in the plates 21, each of the latter is provided with downwardly extending flanges 23 so located as to limit the range of movement of the balls. 50 For limiting the movement of the leaf supporting members 13, there is provided in one of the members 9, a vertical screw 24, Fig. 3, which extends through the adjacent plate 19 and between two of the flanges 23. 55 For releasably locking the leaf supporting members 13 in the rearward position shown in Fig. 5, there is vertically slidably mounted in a vertical hole 25, provided in one of the members 13, a vertical bolt 26, Fig. 6, which extends through a vertical hole in the adjacent plate 21 and is adapted to enter a vertical hole 27 in the adjacent plate 19, Fig. 5. Attached to the bolt 26 is a transverse pin 28, which extends outwardly

through a vertical slot 29 provided in the 65 adjacent member 13.

Mounted in the hole 25, is a vertical coil spring 30, Fig. 6, the lower end of which bears against the bolt 26, and the upper end of which bears against the adjacent 70 member 13. The spring 30 normally forces the bolt 26 downwardly to the locking position.

In order that the leaf supporting members 75 may be locked in the registering position, shown in Figs. 1, 2, 3 and 4, the plate 19 is provided with a vertical hole 31, Fig. 5, adapted to receive the bolt 26.

For supporting the clamping member 3 and the cover 8, there is provided a rearwardly and downwardly inclined plate 32, Figs. 3, 4 and 5, which is secured to the upper inclined edges of the members 9 forward of the transverse bar 11.

In the operation of the invention, the 80 cover 7 is placed in the rearwardly and upwardly inclined position on the members 13 in the notches 15, as shown in Fig. 1. The clamping member 3 is mounted on the plate 32 in a longitudinal inclined position 90 with its outer longitudinal edge resting against the gage plate 12 and with its rear end against the gage bar 11, the plate 12 and bar 11 serving to position the member 3 longitudinally on the support and at right angles to the bar 11 and to the portion 17 which registers the adjacent side edges of the leaves. The loose leaves are then all placed in an inclined position on the cover 7 with their lower edges resting on the portion 16 of the registering plate and with the lines of printed matter 6' parallel with the registering portion 16. The rear edge of the cover 8 rests against the bar 11.

The loose leaves 4 are then shifted one by one in the posting operation to the top of the cover 8 and the clamping member 3 with the edges adjacent to the holes 5 resting against the flange 18 and the lower edges of the leaves resting against the forward side of the portion 17 of the registering plate. In this position of the leaves, the holes 5 will register with the holes in the member 3 which receive the posts 2, and the printed lines 6' will be at right angles to the member 3 so as to be read from left to right.

After all the leaves have been transferred and registered against the portion 17 and the flange 18, the posts 2 are passed downwardly through the holes 5 and into engagement with the clamping member 3, as shown in Fig. 4, with the clamping member 1 resting on top of the portion 17 of the registering plate.

The bolt 26 is then lifted by means of the pin 28 to release the bolt from the plate 19, at which time, the leaf supporting mem-

bers 13 and the plate 16-17 can be forced rearwardly to the position shown in Fig. 5, when the coil spring 30 will force the bolt 26 into the hole 27, thus locking the 5 leaf support in the rear position. The clamping member 1 can then be forced downwardly until it clamps the leaves tightly against the member 3, the latter being at this time locked in the usual manner to the post 2. The leaves will thus be 10 tightly held in the binder, after which the binder may be removed from the posting mechanism.

The bolt 26 may then be lifted to the unlocked 15 position and the leaf support again moved forwardly to the registering position shown in Fig. 1, at which time the bolt 26 is released and enters the hole 31. The mechanism is now in position for another 20 posting operation.

It will be noted that after the leaves have been properly registered, the posts 2 may be inserted through the holes 5 and into engagement with the clamping member 3, thereby 25 holding the leaves in the proper position, so that the movable leaf support may be moved out of the registering position prior to the leaves being clamped, and that this operation may be effected with an ordinary 30 two-post binder without the use of auxiliary locking pins or other auxiliary devices. With our improved posting device, loose leaves which have the lines of printed matter running at right angles to the clamping 35 members of the binder, can be easily read and readily transferred to the registering position during the posting operation, and with either side of each leaf facing upwardly.

40 We do not limit our invention to the structure shown and described, as many modifications, within the scope of the appended claims, may be made without departing from the spirit of our invention.

45 What we claim is:—

1. In a posting mechanism, a support for a clamping member of a binder, and leaf-registering means arranged to engage two adjacent edges of each of a plurality of 50 loose leaves carried on said member, said support having means for properly positioning said clamping member, said registering means being movable to and from the registering position in a direction parallel with the central vertical longitudinal plane of 55 said clamping member.

2. In a posting mechanism, a support for a clamping member of a binder having means for longitudinally positioning said member, 60 a leaf support movable on said support in a direction parallel with the central vertical longitudinal plane of said clamping member, and leaf-registering means carried by said leaf support and arranged to engage edges 65 of loose leaves carried by said clamping

member and movable with said leaf support to and from the registering position.

3. In a posting mechanism, the combination with two clamping members of a binder, one having two posts adapted to operatively 70 engage the other member, of a support for said other member having means for longitudinally positioning said other member, a movable leaf support, and leaf-registering means arranged to engage two adjacent 75 edges of each of a plurality of loose leaves carried by said other member, said leaf-registering means being carried by and movable with said leaf support in a direction 80 parallel with the central vertical longitudinal plane of said other member to and from the registering position, said posts being insertible through said leaves and into operative engagement with said other member while the positioning means and registering means are respectively operatively engaging said other member and said leaves.

4. In a posting mechanism, the combination with two clamping members of a binder, one having two posts adapted to operatively 90 engage the other member, of a support for said other member having means for longitudinally positioning said other member, a leaf support movable in a direction parallel with the central vertical longitudinal plane 95 of said other member and arranged to hold loose leaves in an inclined position, and leaf-registering means carried by said leaf support and movable therewith to and from the registering position and arranged to 100 engage two adjacent edges of each of a plurality of leaves carried by said other member, said posts being insertible through the leaves carried by said other member and into operative engagement with said other member while said positioning and registering means are in the operative positions.

5. In a posting mechanism, a support for a clamping member of a binder having means for longitudinally positioning said member, a leaf support movable on said support in a direction parallel with the central vertical longitudinal plane of said member, and a registering plate disposed at right angles to said member and carried by said leaf support and arranged to engage one set of edges of loose leaves carried by said member.

6. In a posting mechanism, a support for a clamping member of a binder having 110 means for longitudinally positioning said member, a leaf support movable on said support in a direction parallel with the central vertical longitudinal plane of said member, and a registering plate carried by said leaf support and disposed at right angles to the direction of movement of said leaf support and arranged to engage one set of edges of loose leaves carried by said member and having a flange arranged to engage 115 120 125 130

adjacent edges of the leaves carried by said member.

7. In a posting mechanism, a loose leaf having two pairs of post-receiving holes respectively adjacent to opposite end edges of the leaf and spaced apart at equal distances from the end edges and from one side edge

of the leaf, and having lines of printed matter running at right angles to said end edges, substantially as set forth.

In testimony whereof we have signed our names to this specification.

CHARLES R. FARGO.
PAUL O. UNGER.
